HAROLD A. WHEELER, OF GREAT NECK, NEW YORK, ASSIGNOR TO HAZELTINE CORPORATION, A CORPORATION OF DELAWARE

THERMIONIC AMPLIFIER

Application filed August 17, 1929, Serial No. 386,544, and in England July 8, 1930.

This invention relates to electric wave repeating apparatus and more especially to thermionic amplifiers adapted principally for amplifying electrical waves in the audio-frequency range.

An object of the invention is to provide an amplifier of the type specified which while utilizing no biasing battery or initial negative biasing potential on the control circuits, or grids, of the amplifier tubes is nevertheless adapted to provide a high degree of substantially distortionless amplification at large volume levels.

A further object is to provide an amplifier of the type specified having a low output impedance and which requires a relatively low space current supply source for the anode circuit of the amplifier tubes resultant upon the omission of the permanent biasing potential from the grids thereof.

The amplifier as disclosed herein requires a pair of vacuum tubes for each stage of amplification. Due to the particular manner in which these tubes are interconnected, separate sources of cathode and anode current are in general required for the respective tubes. Accordingly, a further object of the invention is to provide an amplifier of the type specified wherein common sources of cathode and anode current may be utilized for supplying the tubes.

As a general proposition, one of the essential requisites to distortionless amplification by means of thermionic amplifiers, particularly at the higher energy levels, consists in the provision of a sufficient permanent negative biasing potential on the grids of the tubes to maintain the grids at all times negative during signal reception. The effect of the impressed signaling current carrying the grid positive during a portion of each cycle is to permit the flow of grid current in the input circuit during such intervals which causes a potential drop therein and thus correspondingly reduces the signaling voltage applied to the tubes which results in distortion and limitation of output.

Even where the grids of the tubes are maintained sufficiently negative by a biasing potential, distortion is in general introduced

into the repeated signal due to the non-linear grid voltage-plate current characteristic of the amplifier tubes. As a result of this factor the positive portions of the impressed signal are amplified to a greater extent than the negative for the reason that the tube works over a different portion of its voltage-plate current characteristic when repeating the positive than when repeating the negative portions of the wave.

The present invention provides an amplifier which while dispensing with the initial or permanent negative biasing potential on the grids, eliminates the objectionable effects due to the grids being carried positive by the signaling waves. In addition, the operation of the amplifier is such that the same portion of the grid voltage-plate current characteristic of the tubes is utilized for amplifying both the positive and negative portions of the impressed signaling waves which, of course, reduces to a minimum, distortion due to the non-linearity of such characteristic.

The above unique results are obtained by utilizing a pair of similar vacuum tubes for each amplifier stage. One terminal of an input circuit is connected directly to the cathode of one tube and thru a high impedance element, preferably a resistance, to the grid of the other tube. Correspondingly, the second input terminal is connected directly to the cathode of the second tube and thru a similar high impedance element to the grid of the first tube. Since the cathodes of the respective tubes are connected to opposite terminals of the input circuit the usual methods of supplying current to the cathodes and anodes thereof from common sources of supply would result in short-circuiting the input circuit. As a result, therefore, in general separate sources of supply are required and it is necessary to couple the anode circuits of the tubes with the output circuit thru separate primary windings of a three winding transformer, the secondary of which is connected between the output terminals. The primary windings are so poled that the signaling waves repeated by the tubes produce additive effects in the output circuit.

Due to the opposite manner in which the tubes are connected to the input circuit, the grid of one tube will be carried positive by the impressed signaling wave at each instant that the grid of the other tube is carried negative. Current will flow in the grid circuit of the tube having its grid positive, but this grid current will be limited to a very small value since it must flow thru the high impedance element connected to the corresponding grid. As a result, the grid current will produce an inappreciable voltage drop in the input circuit and will thus have a negligible effect in reducing the effective signaling voltage applied to the input sections of the tubes. Furthermore, since the same amount of grid current will flow in the input section for both positive and negative portions of the signaling wave, there will be no distortion effects due to unequal voltage drops in the input section for the positive and negative wave portions respectively.

As a result of the flow of grid current, each tube is substantially inactive as regards repeating the signal during the intervals that the grid thereof is carried positive by the signaling wave. This is due to the fact that practically all of the signaling voltage impressed upon the input section of such tube is used up in overcoming the potential drop resulting from the flow of grid current thru the high impedance element. As a consequence, very little of the signaling voltage is applied between cathode and grid of the tube and hence such tube repeats the signal weakly to the output circuit. On the other hand, the tube having its grid carried negative by the signaling wave offers practically an open circuit impedance to the flow of grid current so that the full signaling voltage is applied directly between grid and cathode thereof, since none is lost in potential drop across the high impedance element, and accordingly such tube strongly repeats the signal. Thus each tube repeats signals only during the interval that its grid is maintained negative by the signaling wave with the result that both positive and negative portions thereof are amplified with the tubes working over the same portion of the grid voltage-plate current curve.

The arrangement for supplying the tubes from common cathode and anode sources is best explained by reference to the drawing of which:

Figure 1 shows the circuit diagram of an amplifier embodying the novel features of the present invention but using separate sources of cathode and anode current for the respective tubes.

Fig. 2 shows a modification of Fig. 1 where in common potential sources of cathode and anode current are utilized for supplying all of the amplifier tubes. Fig. 2 shows further an arrangement whereby the anode circuits

of the respective tubes are connected directly to a loud speaker of special construction.

The expression "oppositely connected in parallel" applied to the connection of the input circuits of the amplifier tubes, throughout the specification and claims designates the circuit arrangement illustrated in the drawing wherein the cathodes of the amplifier tubes are connected to the respective input terminals and the grid of each tube is connected through impedance means to the cathode of the opposite tube.

Referring to Fig. 1, the amplifier comprises a pair of similar vacuum tubes V_1 and V_2 each having grid G, cathode or filament F, and anode or plate electrodes P. Separate batteries 1 and 3 are utilized to heat the filaments of tubes V_1 and V_2 , respectively. The input circuits of the vacuum tubes are associated with a pair of input terminals I thru a transformer T_1 having the primary P_1 thereof connected directly to said terminals and having the upper terminal of the secondary winding S_2 thereof connected directly to the negative terminal of the filament F of tube V_1 and connected thru a high resistance R_2 to the grid of tube V_2 . Similarly, the lower terminal of secondary S_1 is connected directly to the negative terminal of the cathode of tube V_2 and also thru a high resistance R_1 to the grid of tube V_1 . The output circuit comprises a three-winding transformer T_2 having a single secondary winding S_2 connected directly to a pair of output terminals O and a first primary winding P_2 connected from the plate of the tube V_1 thru a space supply source 2 to the cathode of the tube. A second primary winding P_3 is similarly connected from the plate of tube V_2 thru a second space supply source 4 to the cathode of tube V_2 . The primary windings P_2 and P_3 are poled relatively so that the steady space supply currents flowing thru the respective windings produce opposing magnetic fluxes in the transformer core.

The resistances R_1 and R_2 are, of course, similar in magnitude having a value of from .1 to 1.0 megohm dependent upon the type of tubes used. Any suitable high impedance elements traversable by uni-directional current could be utilized in place of the resistance elements. For example, choke coils would in some instances be well adapted to this purpose.

In the operation of the amplifier, when an incoming signaling wave is applied to the input terminals I in such manner that the upper terminal of S_1 is negative relative to the lower terminal thereof, the grid of tube V_1 will be carried positive and that of tube V_2 negative by the signaling voltage. Under such conditions, the current will flow from the upper terminal of S_1 to the filament of tube V_1 and thence thru the space path from filament to grid thereof, returning thru the

resistance R_1 and the winding S_1 to the upper terminal of winding S_1 . The resistance R_1 , being of large magnitude will, of course, limit the flow of grid current to a relatively small value, and furthermore due to the relatively small cathode-to-grid resistance of the tube compared to the resistance R_1 , practically the entire voltage of the impressed signal wave will be across the resistance and very little between the filament and grid of tube V_1 . The advantages of this combination of factors have been explained above.

On the other hand, the applied signaling wave being impressed between grid and filament of tube V_2 in a negative sense, the impedance offered from grid to filament thereof amounts to practically an open circuit so that no current will flow in the series circuit comprising the winding S_1 , resistance R_2 and the space path between grid and filament of tube V_2 . As a result, the entire voltage of the signal wave will be impressed between grid and filament of tube V_2 , which thus strongly repeats the signal in the primary winding P_2 of transformer T_2 . At the same time, tube V_1 , due to its positive bias, is weakly repeating the signal in the transformer winding P_2 .

During the succeeding half cycle of the applied signaling wave, namely, while the lower terminal S_1 is negative relating to the upper terminal thereof, the conditions described above will be reversed so that current will flow in the grid circuit of tube V_2 whereas no current will flow in that of tube V_1 . During this half cycle, therefore, tube V_1 will strongly repeat the signal to the output circuit, and tube V_2 will repeat the same to a practically negligible extent.

It will thus be seen that with the circuit arrangement described only one tube at a time is active in repeating the signal. Tube V_1 , for example, will repeat all the positive half cycles of the applied signal wave, whereas tube V_2 will repeat all the negative half cycles thereof, or vice versa. The signaling wave flowing in the output circuit is therefore made up of half cycles for which each tube is always working over the same portion of its grid voltage-plate current characteristic, and hence, the repeated wave is substantially distortionless.

It is obvious from an inspection of Fig. 1 that the replacement of batteries 1 and 3, and 2 and 4 by common sources of potential would result in substantially short-circuiting the secondary winding of the transformer T_1 since a conductive path would be formed between the terminals of the secondary winding S_1 thru the common source of supply.

Fig. 2 shows an arrangement for utilizing common sources of cathode and anode supply without effectively short-circuiting the input circuit to the amplifier tube.

Referring to Fig. 2, the input transformer T_1 comprises a primary winding P_1 con-

nected to the input terminals I and four similar secondary windings S_1 to S_4 , inclusive, wound on the same core as primary winding P_1 . The secondary windings S_1 to S_4 are so poled that a current active in the primary winding induces voltages in the various secondary windings in the relative directions indicated by the arrows.

The secondary windings S_1 and S_3 are serially connected between the plates of tubes V_1 and V_2 , respectively, over a circuit traced from the plate of tube V_1 over lead 12 thru a winding 6 of a loud speaker unit L, over lead 11 thru the windings S_1 and S_3 in series, over lead 13, thru a second winding 7 of the loud speaker L and over lead 19 to the plate of tube V_2 . Windings S_2 and S_4 are serially connected between the midpoints of impedance elements 1 and 2 bridged across the cathodes of tubes V_1 and V_2 , respectively. A common space current supply source 17 for the anode circuits of the tubes is connected from a point between windings S_2 and S_4 to a point between windings S_1 and S_3 . The cathodes of tubes V_1 and V_2 are connected respectively to the secondary windings 15 and 16 of a transformer T_2 having its primary winding connected to a pair of terminals 14, whereby a common source of alternating current connected to terminals 14 will heat the filament of both tubes.

The grids of tubes V_1 and V_2 are connected thru resistance elements R_1 and R_2 to the outer terminals of windings S_4 and S_2 , respectively. The capacities C are bridged across the outer terminals of windings S_1 and S_2 , and S_3 and S_4 , respectively, to equalize the fluctuating currents flowing in the transformer windings, and thus prevent undesired reactions between the input and output circuits of the tubes and also to bypass the amplified signaling currents flowing in the anode circuits of the tubes.

In the operation of the amplifier the space supply current for tube V_1 , considering now the true direction of current flow, flows from the negative terminal of battery 17 thru the winding S_2 to the midpoint of impedance 1, whence it divides equally and flows in both directions to the filament F of tube V_1 , and thence in the space path to the plate P, returning over lead 12, winding 6 of speaker L, lead 11, and thru the winding S_1 to the positive terminal of the battery. It will be noted that the space current flowing in the circuit traced flows thru the windings S_1 and S_2 in such relative directions that the fluxes set up cancel one another so that the resultant flux due to the steady space current is zero. The space current for tube V_2 flows in a similar manner from the negative terminal of battery 17 thru winding S_4 to the midpoint of impedance element 2, whence it divides, flowing equally in both directions to the filament F of the tube and thence in the space

path from filament to plate P thereof, returning over lead 19 and thru winding 7 of speaker L, over lead 13 and thru the winding S₃ to the positive terminal of battery 17. It will be noted that the current flows in windings S₃ and S₄ in such relative directions that the fluxes set up cancel each other.

Assuming now a signaling voltage to be impressed upon the input terminals I, the voltage induced in windings S₂ and S₄ will be impressed in an additive sense upon the input sections of tubes V₁ and V₂, since these windings are serially connected thereacross. Assuming at a given instant the signaling voltage to be such that the upper terminal of winding S₂ is negative relative to the lower terminal of winding S₄, the grid of tube V₁ will be carried positive and that of tube V₂ negative by the signaling wave. As a result, current will flow in the grid circuit of tube V₁ which circuit is traced from the grid of tube V₁ thru resistance element R₁, windings S₄ and S₂ in series to the midpoint of impedance 1 and thence in both directions to the filament of tube V₁ and back to the grid thru the space path of the tube, producing the effects pointed out above in connection with Fig. 1. Since the grid of tube V₂, on the other hand, is carried negative by the impressed voltage, the full voltage of windings S₂ and S₄ in series is impressed between the grid and cathode of tube V₂ thru the resistance element R₂ and the impedance element 2. When the applied signaling voltage is such that the lower terminal of winding S₄ is negative relative to the upper terminal of winding S₂ conditions will be reversed, the grid of tube V₁ being carried negative and that of tube V₂ positive by the signaling wave. It will thus be seen that the signaling voltages are impressed upon the amplifier tubes of Fig. 2 in the same manner as for the amplifier of Fig. 1.

Due to the relative polarities of windings S₁ and S₂ and windings S₃ and S₄ a voltage active in the primary winding of transformer T₁ produces no effect in the anode circuits of tubes V₁ and V₂. Considering the anode circuit of tube V₁, if the voltage in the primary winding P₁ is such as to produce a voltage in the direction indicated by the arrow in winding S₂, it will produce an equal voltage in the direction indicated by the arrow in winding S₁, and since the lower terminals of windings S₁ and S₂ are in effect short-circuited thru the battery 17, the voltages in the two windings will buck each other and thus set up no resultant current in the anode circuit of tube V₁. In a similar manner, a current active in the primary winding P₁ will produce no effect in the anode circuit of tube V₂ since, assuming the primary current to be such as to induce a voltage in winding S₄, as indicated by the arrow, it will also induce an equal voltage in winding S₃ as indicated by its arrow, and these voltages will annul each other producing no resultant effect in the anode circuit of tube V₂.

Conversely, the amplified signaling currents flowing in the anode circuits of tubes V₁ and V₂, respectively, will produce no effect in the primary winding P₁ of the transformer T₁. In the first place, a large portion of the amplified signaling current flowing in the anode circuits of the tubes will be by-passed around the transformer secondary windings by the capacities C. Any amplified signaling current in the anode circuit of tube V₁, however, which flows thru the secondary windings of the input transformer will flow in one direction thru winding S₁ and in the opposite direction thru winding S₂ with the result that the fluxes will annul each other and induce no voltage in the primary winding P₁. Similarly, amplified signaling current flowing in the anode circuit of tube V₂ will flow in one direction thru winding S₃ and in the opposite direction thru winding S₄ producing zero resultant effect upon primary winding P₁.

The connection of the input circuit to the cathodes of tubes V₁ and V₂, respectively, thru the midpoints of the impedance elements 1 and 2 prevents the grids from being affected by the alternating current supply utilized for heating the cathodes of the tubes and thereby eliminating any hum due to the cathode supply source.

In Fig. 2, the anode circuits of the tubes are connected respectively to a pair of signal current actuating windings of a special type of loud speaker unit known as the "Farrand inductor dynamic" speaker. The loud speaker L comprises a permanent horseshoe magnet 3 having affixed to the inner surfaces of the poles thereof, respectively, a pair of U-shaped pole pieces 4 and 5 of soft iron or other easily magnetizable material. The pole pieces are so positioned that corresponding legs thereof are opposed leaving small air gaps therebetween in which is positioned a vertically movable armature 8 rigidly affixed by means of a rod 9 to the center of a cone loud speaker unit 10. A signal current coil 6 is placed about the upper leg of pole piece 4 and a similar coil 7 is placed about the lower leg of pole piece 5. These coils are connected respectively in the anode circuits of tubes V₁ and V₂ as was explained above, being so poled that the steady space currents of the tubes flowing therethru in each case set up a flux in the same direction as that of the permanent magnet 3.

The armature 8 has a length slightly less than the distance between the outer surfaces of the pole piece legs, being positioned symmetrically in the air gaps and thus pulled equally in opposite vertical directions by the steady fluxes threading the upper and lower air gaps between the opposed legs of the pole

pieces 4 and 5. If, however, a signaling wave be impressed upon the input terminals I of the amplifier, the action of the amplifier is such that the current in signal coil 6 decreases when the grid of tube V_1 is negative, and at the same time the current in signal coil 7 remains constant at the normal direct current value or increases very little, because the grid of tube V_2 is positive. Likewise, when the grid of tube V_1 is positive, the current in signal coil 6 is practically at the normal direct current value and the current in signal coil 7 is decreased. From the foregoing it is seen that the signal coils are alternately operative and furthermore the coil which is inoperative exerts no influence upon the coil which is operative. This gives the result that the inactive tube of low plate resistance is not effectively a shunt across the output of the active tube, as would be true if a single output transformer were utilized.

The principal advantage of connecting the inductor type loud speaker directly in the anode circuits of the amplifier tubes is that all of the frequencies operate on the speaker unit to equal advantage, whereas if the speaker were connected to the terminals of an output transformer, as for example terminals O of Fig. 1, the lower frequencies would in general be discriminated against. Another advantage of the arrangement of Fig. 2 lies in the elimination of the output transformer T_2 which represents an economy of construction. The greatest distortionless power output is secured when there is practically no mutual magnetic coupling between coils 6 and 7 and when the effective impedance of each coil is approximately three times the output impedance of the vacuum tubes individually connected thereto.

Referring back for a moment to Fig. 1, where signals varying in intensity from weak to strong are apt to be received, the distortionless operation of the amplifier is improved by making the resistances R_1 and R_2 equal to the dynamic grid-filament impedances of the corresponding tubes measured at such weak intensities. For small impressed voltages, the cathode to grid resistances of the tubes are very large, so that both tubes are about equally active at each instant in amplifying the impressed signal waves. At high intensities, however, the cathode to grid tube resistances drop to a relatively low value so that the resistances R_1 and R_2 become large in comparison and the operation is that described above where in the tube having its grid carried positive by the signalling wave is substantially inactive in repeating the signal.

It thus results that with the above proportioning of the elements R_1 and R_2 , a substantially constant degree of amplification is obtained at all signal intensities. At low intensities one-half the impressed signal volt-

age is at each instant impressed between grid and filament of each tube and since both tubes are active at all times, in repeating such signals the same degree of amplification is obtained as at high intensities where the full signaling voltage is applied at each instant to only one tube, the other tube being substantially inactive.

What is claimed is:

1. In an amplifying system for electric waves, a pair of thermionic valves each including an input section, means connecting said input sections in parallel to a pair of input terminals but in a reversed sense relatively, said means comprising high impedance elements connected between said terminals and said input sections adapted to cause signal waves present in said input sections to be impressed in substantial entirety upon the valve which momentarily receives a negative potential therefrom, whereby said latter valve alone repeats the signal.

2. In a thermionic amplifying system for electric waves for providing a high degree of substantially distortionless amplification in the absence of permanent biasing potentials in the control circuits of the thermionic elements, a pair of thermionic valves each having a substantially unilateral input section, means connecting said input sections in a reversed sense relatively between a pair of input terminals, said means comprising high resistance elements connected between said terminals and said input sections, adapted to cause signal waves present in said input sections to be repeated in substantial entirety by the valve which receives a negative potential therefrom, whereby said latter valve alone repeats the signal.

3. In an amplifying system in combination, a pair of thermionic valves each having an input section including grid and cathode, means connecting said input sections in parallel in a reversed sense relatively to a pair of input terminals, and means included in each said input section for substantially preventing the flow of grid current therein, said means comprising high impedance elements connected between said terminals and said input sections, adapted to cause signal waves present in said input sections to be repeated in substantial entirety by the valve which receives a negative potential therefrom, whereby said latter device alone repeats the signal.

4. In a thermionic amplifying system, for providing a high degree of substantially distortionless amplification in the absence of biasing potentials in the control circuits of the thermionic elements, a pair of thermionic valves each having an input section including a grid and a cathode, means connecting said input sections in a reversed manner relatively between a pair of input terminals, and means included in said input sections effective to limit to a small

signal voltage impressed therebetween, means included in said input sections for rendering said tubes substantially inactive while their grids are positive, and means coupling said output sections in opposition to an output circuit, whereby equal positive and negative voltages applied to said input terminals produce equal positive and negative effects in said output circuit and whereby electric waves impressed upon said input terminals are repeated in said output circuit at each instant by the tube having the negative grid.

11. A thermionic amplifying system adapted to provide a high degree of substantially distortionless amplification in the absence of biasing potentials in the control circuits of the thermionic elements, comprising a pair of thermionic tubes each having an input section including grid and cathode, and an output section, means connecting the cathode of the first of said tubes to a first input terminal and the cathode of the second of said tubes to a second input terminal, a high resistance element connecting the cathode of the first of said tubes with the grid of the second of said tubes and a similar high impedance element interconnecting the remaining grid and cathode, means similarly connecting the grid of the second tube thru a resistance and the cathode of the first tube to a second input terminal and means connecting said output sections in opposition to an output circuit, whereby signal waves applied across said input terminals are impressed in substantial entirety upon the input section of the tube whose grid momentarily receives a negative potential therefrom, whereby said latter tube alone repeats the signal, and said signal waves are repeated in said output sections regardless of which tube is momentarily repeating the signal.

12. A thermionic electric wave repeating apparatus for providing a high degree of substantially distortionless amplification in the absence of biasing potentials in the control circuits of the thermionic elements, comprising a pair of input terminals, input and output circuits, a pair of vacuum tubes each including a cathode and grid, one of said cathodes being connected to one input terminal, the other of said cathodes being connected to the other input terminal, said grids being connected oppositely in said input circuit, means interposed between said grids and said input circuit for rendering one tube substantially unresponsive to positive portions and the other substantially unresponsive to negative portions of electric waves in said input circuit said means comprising a pair of resistance elements one of which is connected in series with each grid, the end of each resistance element remote from the grid being connected to the cathode of the other tube, whereby the negative portion of the wave is repeated by one tube and the positive portion by the other tube in said output section.

13. A thermionic amplifier comprising a pair of vacuum tubes each having an anode, cathode and grid, means connecting the grids thereof oppositely across a first impedance means, means connecting said anodes respectively to opposite terminals of a second impedance means, and an anode supply source connected between intermediate points of said first and second impedance means, said impedance means being so coupled to each other and to an input section that electric waves active in said input section are effective upon said grid circuits but electric waves active in the anode circuits of said tubes are ineffective upon said input and grid circuits.

14. A thermionic amplifier comprising a pair of vacuum tubes having the grid circuits thereof connected oppositely across a first pair of serially connected windings and the anodes connected respectively to opposite terminals of a second pair of serially connected windings, and an anode supply source connected from a point between said first pair of windings to a point between said second pair of windings, said windings being so coupled to each other and to an input circuit that electric waves active in said input circuit are effective upon said grid circuits but electric waves active in the anode circuits of said tubes are ineffective upon said input and grid circuits.

15. A thermionic amplifier comprising a pair of vacuum tubes having the grid circuits thereof connected oppositely across a first pair of serially connected windings and the anodes connected respectively to opposite terminals of a second pair of serially connected windings, an anode supply source connected from a point between said first pair of windings to a point between said second pair of windings, said windings being so coupled to each other and to an input circuit that electric waves active in said input circuit are effective upon said grid circuits, but electric waves active in the anode circuits of said tubes are ineffective upon said input and grid circuits, and a capacity connected from each outer terminal of said first pair of windings to the corresponding outer terminals respectively of said second pair of windings.

16. A thermionic amplifier comprising a pair of vacuum tubes each having anode, cathode and grid electrodes, means for heating said cathodes from a common source comprising a transformer having secondary windings individually connected to said cathodes respectively, impedance elements bridged between the terminals of each said cathode, a first pair of windings serially connected from an intermediate point of said first to an intermediate point of said second impedance element, a second pair of windings serially interposed between the anodes of said tubes respectively, an anode supply

- source connected from a point between said first to a point between said second pair of windings, means connecting the grid of each said tube thru an impedance to the cathode of the other tube, said windings being so coupled to each other and to an input circuit that electric waves active in said input circuit are effective upon the grid circuits of said tubes, but electric waves active in the anode circuits thereof are ineffective upon said input and grid circuits, and means separately coupling the anode circuits of said tubes to a load. 70
17. A thermionic amplifier comprising a pair of vacuum tubes each having anode, cathode and grid electrodes, means for heating said cathodes from a common source including a transformer having secondary windings individually connected to said cathodes, impedances bridging the terminals of each said cathode, an input transformer having a first secondary winding extending between intermediate points of said impedances respectively, and a second secondary winding connected between the anodes of said tubes respectively, an anode supply source connected between corresponding intermediate points of said second first and said secondary windings, means connecting the grid of each tube thru an impedance to the cathode of the opposite tube, said secondary windings being so coupled to each other and to a primary winding that electric waves active in said primary are effective upon the grid circuits of said tubes, but electric waves active in the anode circuits thereof are ineffective upon said primary winding and said grid circuits, and output windings individual to the anode circuits of said tubes respectively, said output windings being magnetically coupled to a load. 90
18. The combination with a thermionic amplifier for providing a high degree of substantially distortionless amplification in the absence of biasing potentials in the control circuits of the thermionic elements, comprising a pair of vacuum tubes each having an anode, a cathode and a control electrode and having the grid circuits thereof connected oppositely to an input circuit, a first high impedance element connecting the cathode of one tube to the grid of the other tube and a second high impedance element connecting the remaining grid and cathode and said cathodes being connected respectively to said input terminals whereby signaling waves applied across said input terminals are impressed in substantial entirety upon the tube which receives a negative potential therefrom so that said latter tube repeats the signal of a loud speaker unit including means for producing a permanent magnetic flux adapted to maintain in dynamic equilibrium an armature affixed to an acoustical unit, a pair of signal current coils for actuating said armature situated respectively adjacent opposite ends thereof, means so connecting said coils individually in the anode circuits of said tubes respectively that the fluxes due to the space currents flowing in each case aid said permanent flux, whereas signal waves repeated by said tubes produce additive effects upon said armature at any instant, regardless of which tube is repeating the signal. 100
19. In a wave repeating system, a pair of input terminals, a pair of output terminals, a pair of impedance elements and a pair of repeating elements, each of which has an input circuit and an output circuit, the input circuit of one of said repeating elements being arranged in series with one of said impedance elements, the input of the other of said repeating elements being arranged in series with the other of said impedance elements, said series arrangements being connected in parallel in an opposite sense to said input terminals so that the ends of said impedance elements remote from the associated input circuits are connected to opposite input terminals, whereby signal waves applied across said input terminals are impressed in substantial entirety upon the input circuit of the repeating element which receives a negative potential therefrom so that said latter repeating element repeats the signal. 110
20. In a thermionic wave repeating system for providing a high degree of substantially distortionless amplification in the absence of negative biasing potentials in the control circuits of the thermionic elements, in combination, a pair of input terminals, a pair of impedance elements, and a pair of thermionic repeating elements, each of said repeating elements comprising a cathode, anode and grid, one of said impedance elements having one of its terminals connected to the first of said input terminals and its other terminal connected to the grid of the second of said repeating elements, the cathode of said second repeating element being connected to the second of said input terminals, and the other of said impedance elements having one of its terminals connected to the second of said input terminals and its other terminal connected to the grid of the first of said repeating elements, the cathode of said first repeating element being connected to the first of said input terminals, whereby signal waves applied across said input terminals are impressed in substantial entirety upon the repeating element whose grid receives a negative potential therefrom, so that said latter repeating element repeats the signal. 120
21. In a thermionic amplifying system for providing a high degree of substantially distortionless amplification in the absence of negative biasing potentials in the control circuits of the thermionic elements, in combination, a pair of input terminals, a pair of high impedances and a pair of space discharge 130

devices, each of said devices comprising a cathode, anode and control electrode, said impedances and discharge devices being connected to said input terminals in the following manner; cathode of the first of said devices to one terminal of the first of said impedances, the other terminal of the first of said impedances to the control electrode of the second of said devices, the cathode of the second of said devices to one terminal of the second of said impedances, the other terminal of the second of said impedances to the control electrode of the second of said devices, one of said input terminals being connected to one cathode and the other input terminal to the other cathode, whereby signal waves applied across said input terminals are impressed in substantial entirety upon the device whose control electrode momentarily receives a negative potential therefrom, so that said latter device is alone effective to repeat the signal.

22. The combination of claim 21 in which said impedances are resistance elements.

23. In testimony whereof I affix my signature.

HAROLD A. WHEELER.

Certificate of Correction

Patent No. 1,878,742.

September 20, 1932.

HAROLD A. WHEELER

It is hereby certified that error appears in the printed specification of the above-numbered patent requiring correction as follows: Page 1, line 57, before "voltage—" insert the word *grid*; page 2, line 53, for "drawing" read *drawings*; and same page, line 89, for "S," read *S₁*; and that the said Letters Patent should be read with these corrections therein that the same may conform to the record of the case in the Patent Office.

Signed and sealed this 29th day of November, A. D. 1932.

[*initials*.]

M. J. MOORE,
Acting Commissioner of Patents.

devices, each of said devices comprising a cathode, anode and control electrode, said impedances and discharge devices being connected to said input terminals in the following manner; cathode of the first of said devices to one terminal of the first of said impedances, the other terminal of the first of said impedances to the control electrode of the second of said devices, the cathode of the second of said devices to one terminal of the second of said impedances, the other terminal of the second of said impedances to the control electrode of the second of said devices, one of said input terminals being connected to one cathode and the other input terminal to the other cathode, whereby signal waves applied across said input terminals are impressed in substantial entirety upon the device whose control electrode momentarily receives a negative potential therefrom, so that said latter device is alone effective to repeat the signal.

22. The combination of claim 21 in which said impedances are resistance elements.

23. In testimony whereof I affix my signature.

HAROLD A. WHEELER.

Certificate of Correction

Patent No. 1,878,742.

September 20, 1932.
